FARM GATE

Lewis Beard, New Boston, Ill.

Application February 10, 1938, Serial No. 189,749

2 Claims. (Cl. 39—44)

My invention has reference to a farm gate, and has for its chief purpose to provide a strong, durable, and highly efficient structure of that type. It is of a character to be rockingly mounted, so that by means of levers extending to the sides of the gate it can be tipped upwardly out of the way of traffic, or rocked backwardly into place again. It is of double construction, and self-bracing, so as to resist the force of strong winds when it is in an elevated position.

It is specially adapted for use in countries having winter climates and quantities of snow, and if snow covers the ground about the gate it is merely lifted upwardly out of it, without hindrance therefrom. This is a great advantage over the old style swing gate, which is frequently held from movement by the deep snow surrounding it, and which has to be cleaned away before the gate can be opened. In the present invention, when the gate is returned to position after being opened, it settles downwardly through the snow, effectively closing the passage.

Another object of the invention is to provide a balancing mechanism, by means of which the load of the gate while being operated will be greatly relieved, and the force of which is shiftable to different parts of the gate, as it is raised or lowered. The operation of this mechanism is entirely automatic. As the gate moves downwardly the weight thereof increases, so that it is returned positively to closed position. When the gate is fully raised for the passage of a vehicle, there is no danger of its being carried back into the lane of traffic by the wind, as frequently occurs with the swing type of gate.

Another purpose of the invention is the provision of novel apparatus for applying the force of the levers to the gate, to open or close the same. By this means successive movements of a lever will be effective to alternately open and close the gate, the operation of the lever giving an initial movement to the gate, which movement is followed up by the force of the counterbalancing devices, by which the movement is completed.

Another purpose of the invention is to provide a latch mechanism, to connect the free end of the gate with a post or other fixture when it is in closed position, and prevent accidental movement thereof. The latch can also be used to hold the gate in place when elevated a little ways from the ground, to permit the passage beneath the same of smaller animals.

The invention is of simple construction and operation, and can be produced at a minimum

amount of cost, due regard being had to the strength and durability of the structure.

The above named, and other features of the invention will more fully appear from the following specification, taken in connection with the accompanying drawings, in which is portrayed a preferred form of the invention, and in which—

Fig. 1 shows the invention in side elevation, with the gate closed.

Fig. 2 is an enlarged detail of the latch end of the gate.

Fig. 3 shows the gate lifting mechanism in enlarged fragmentary view.

Fig. 4 is an end view from the arch end of the structure, with the wire fabric omitted.

Fig. 5 is a top plan view of the invention, with the gate in closed position.

Fig. 6 is a side view of the gate in closed position, with one of the side panels removed.

The reference number 10 indicates a beam, or base member, which may be of concrete, and level with the surface of the ground. An arch 11 is rockingly connected with the base 10, by means of said arch are gate panels, formed of pieces 13, 25 united at their free ends by a vertical piece 14. Centrally of the gate are supports 15, and the sides of the panels thus formed may be covered with wire or metal screen, as indicated at 16, to protect the same and increase the durability of the gate. The structure thus formed is of a V-formation, and each of the gate panels tends to support and brace the other, especially when the gate is in an elevated position. When in this position the narrow or pointed part of the gate 30 is uppermost, and the gate is well prepared to meet and resist the force of the elements.

At each side of the gate is mounted a hand-lever 17, by a pivotal connection with a post 18, supported on the beam 10. In the end of the gate 40 containing the arch 11 are fixed wire or rod loops or frames 19 and 20, with which the short end of the lever is connected by means of chains 21 and 22, respectively. The construction of this apparatus is the same at each side of the gate, 45 so that the description of one of these and its operation will answer for both. The long ends of the levers 17 are provided with cords 23, to facilitate the operation thereof, and by pulling down thereon the chain 21 and frame 19 are 50 drawn upwardly, causing the gate to rock on its hinges, and carrying it toward one side of the drive-way. The movement is completed in the manner hereinafter set forth, and when it is desired to close the gate again, this is done by 55

again operating one or other of the levers, actuating the other chain 22, and through its connection with the loop 20, starting the gate downwardly again.

5 The bar 19 is bent upwardly, as shown in Fig. 3, and the last link of the chain 21 has an initial movement to the center of the bar, before it begins to exert a pull on the gate. This pull gives the rocking movement to the gate before mentioned, and in the additional rocking movement the end of the chain has free movement along the bar. The same is true of the bar 20, which is bent in the direction of the small end of the gate, and on which the end of the chain 22 is slideable a 10 little ways before it begins to exert a pull. The gate, which is in the position shown in broken lines in Fig. 1, is tipped downwardly a little ways, and then settles back into place of its own weight. A post or other fixture is provided at the free end of the gate, as shown at 24. This 15 may be the end post in a line of fencing.

The gate is provided with a balancing apparatus, consisting of a bar 25, having a hinged connection with a post 26 as at 27. The outer 20 end of said bar is connected by a chain 29 with a loop 30 of a rod 31, which is slideable in a guide 32 on a cross-bar 33 supported between the pair of supports 15. The outer end of the rod 31 is connected by a chain 34 with the post 30 14. As the gate is elevated the bar 25 is also tipped upwardly by the weight 28 thereon, which may be in the form of a concrete block, bolted thereto. At the highest point the end of the bar 25 is near the free end of the gate, as in 35 broken lines in Fig. 1, the relative movement of such parts being allowed for by a sliding movement of the rod 31 in the guide 32. This not only permits a free action of the gate and bar with reference to each other, but the force of the weight is gradually shifted toward the end 40 of the gate, farther away from the rocking point thereof, and with a greater leverage in the lifting operation. As the gate is lowered again this counterbalance force is gradually diminished, permitting the gate to settle easily 45 into closed position.

The structure is also provided with a locking device, for holding the gate in a closed position, consisting of a latch 35, the end of which engages 50 with detents 36 in a channel in the face of the post 24, to hold the post 14 from upward movement. Engagement of the latch is enforced by a coiled spring 37, and the latch is connected by a rod 38 with the last link of one of the chains 21. The initial movement of such chain in the operation of lifting the gate will move the rod sufficiently to release the latch, and permit the gate to be raised. In the downward movement of the gate the latch will automatical-

ly engage the detents. Under ordinary conditions such engagement will be with the lowest 5 detent, with the gate fully lowered, but if desired the gate can be elevated a little, leaving a space at the bottom, and the latch engaged with the next higher detent.

The manner of operating the gate will be obvious. Upon approaching the gate from one side or the other the hand lever on that side of the gate is operated in a customary manner, causing 10 the gate to be first unlocked, and then tipped upwardly out of the way. After passing through, the other lever is operated, closing the gate again.

The gate itself can be made of pieces of common timber, such as two-by-fours, and is of a strong and durable construction, especially when provided with the wire netting reinforcement. The satisfactory operation of the gate depends 15 chiefly on a simple rocking movement, and there 20 is very little about the mechanism to get out of order.

Changes can be made in the construction of various parts of the device, and in the manner of operation thereof, without departing from the 25 spirit of the invention, as set forth and claimed herein.

What I claim as my invention, and desire to secure, is:

1. A farm gate comprising a pair of panels 30 united in V-form, provided with hinge supports at their wider end, and capable of being rocked into open and closed positions, hand-levers pivotally supported at opposite sides of the gate, connections between said hand-levers and the 35 rocking end of the gate, including pairs of bars on the gate and flexible elements between said bars and the lever, operating to alternately raise and lower the gate, and a balancing apparatus supported between the panels of the gate, and 40 operatively connected with said gate with a shiftable application of force.

2. A farm gate provided with hinge supports at its rear end, capable of being rocked from a horizontal to a vertical position and the reverse, 45 hand-levers pivotally supported at opposite sides of the gate, connections between said hand-levers and the rocking end of the gate, including pairs of rods on opposite sides of the gate and chains attached to the levers having a slideable 50 engagement with said rods, a balancing mechanism supported convenient to the gate, a bar slideable longitudinally of the gate, and flexible connections between said bar and said gate, and between said bar and said balancing apparatus, 55 resulting in a shifting of the force of said mechanism outwardly as the gate is lifted.

LEWIS BEARD.
